WORTH MEDLY BRYARS, OF MERCED, CALIFORNIA

LINE SAFETY DEVICE FOR TYPOGRAPHICAL MACHINES

Application filed February 3, 1932. Serial No. 590,746.

My invention relates to improvements in typographical machines, and has particular reference to machines of the character of the one shown and described in Letters Patent No. 436,532, granted September 16, 1890, to O. Mergenthaler, wherein circulating matrices, when released from a magazine, are made to appear in line in an "assembling elevator" and the composed line transferred through an intermediate channel into a vertically movable "first elevator", which presents same to a mold to form a slug or linotype against the matrices and the latter thereafter elevated and returned through a distributing mechanism to the magazine from which they started.

More particularly, my invention relates to what are known in the art as "line safety devices", and in the particular instance an object of my invention is to provide a mechanism which is simple of construction, reliable in action and one which embodies means for automatically locking the assembling elevator so as to prevent advancing of the mold until either the filling piece of the first elevator has been thrown into one of two positions or the duplex rail of the assembling elevator withdrawn, thus preventing the sending of a line through that is raised in the auxiliary position in the assembling elevator.

In the use of certain prior known line safety devices, such, for instance, the form of device shown in the Letters Patent to Atkins, No. 1,804,487, it has been discovered that when the assembling elevator is raised by the operator considerable friction is set up between the duplex rail and the line safety device at the lower end of the assembling elevator, to the extent that the line of matrices is disturbed, sometimes to the extent of an inch or more, and that this results in sending a line through in a "double black" position.

It is, therefore, an important object of my invention to provide means in a line safety device that will eliminate friction between the duplex rail and any part of the device during the operation of moving the assembling elevator and to provide positive

ly acting means that will prevent a line of matrices from being disturbed incident to end thrust exerted against the duplex rail at a point near the lower end of the transfer channel and from being sent into the machine in said "double black" position. The matrices to which reference is made herein are those of the two letter variety and same are constructed and designed to function in the mechanism to be found in the Rogers Re-issue Patent No. 13,489, wherein provision is made to cast a slug from the lower characters of the matrices of a composed line, as for a solid line of italics, at which time the matrices are maintained at the lower level, and the first elevator arrested in a slightly raised position, so as to locate the selected characters opposite the mold slot, the upper position of said mechanism being controlled by a filler piece situated at the vise cap and adapted to be brought into action at the option of the operator.

To the end herein advanced and others that will manifest themselves as the description proceeds, the invention consists in certain improvements and combinations and arrangements of parts as will be hereinafter fully set forth, with the features of novelty pointed out in the hereto appended claims.

In the accompanying drawings:

Figure 1 is a front view of my improved line safety device, showing the first elevator filling piece in a position ready to actuate the device during movement of the filling piece in the direction of the arrow A, as by a manual actuation imparted thereto;

Figure 2 is a top plan view thereof, with the parts in the position shown in Figure 1, the intermediate transfer channel being illustrated in horizontal section;

Figure 3 is a view in end elevation of the device, with parts shown in section and parts broken away;

Figure 4 is a diagrammatic perspective view of the device, with the filling piece in a position indicating that movement has been imparted to the device to change the position of the locking dog with respect to the duplex rail of the assembling elevator and with the duplex rail pushed in for the auxiliary

position, and with all other parts of the assembling elevator omitted for the purpose of clarity;

Figure 5 is a fragmentary perspective view 5 of a part of the device emphasizing the construction of the locking dog for the duplex rail of the assembling elevator and showing the dog in the path of said duplex rail, all other parts of the assembling elevator being 10 omitted for the purpose of clarity.

In the accompanying drawings, 5 indicates the first elevator filling piece which is hinged to the top of the vise cap 6 and provided with means 6^a for effecting manual manipulation of the blade 6^b; 7 the vise locking screw and 8 an intermediate transfer channel, the latter coacting with the assembling elevator 9 into which the matrices are adapted to be guided and the line composed preparatory to sending same through said intermediate channel for ultimate delivery at the mold, all in a manner common to typographical casting and composing machines. The assembling elevator 9 is provided with a 20 manually adjustable duplex rail 10 which is designed to permit a line of matrices to be supported at the second elevation and to prevent the line from falling to the first elevation until the rail is withdrawn.

To the top of the vise cap 6 is fulcrumed 30 for horizontal movement, as at 13, a lever 14, the same provided with an arcuate branch 15 whose free end is formed with a cam surface 16 which is normally situated in the effective path of movement of the first elevator filling piece 5, and as illustrated to advantage in Figures 1, 2 and 3, inclusive, of the accompanying drawings, the same occupies an acute angle and is preferably beveled to about fifteen degrees from a right angle so that when the filling piece is in full line position shown in Figure 2 said surface will positively reside in the path of the inner edge of the blade 6^b thereof, and motion thereby set up in the lever 14 to tilt it horizontally on its vertical axis. From 40 the vertical fulcrum point 13 the said lever extends angularly across the upper face of the vise cap and in a direction toward the lower end of the assembling elevator, thence proceeding in a direction at right angles to the adjacent side of the vise cap, at which last location said lever is formed with a vertical lug 17 which is positioned in free normal contact with the broad flat face of a lever 18.

The lever 18 is fulcrumed on a vertical axis 19 to the under face of the intermediate transfer channel 8 and same has a vertical post 20 located in juxtaposition to the end of the assembling elevator nearest said transfer channel. The upper end of said post has pivoted thereto for movement in a vertical plane a dog 21, the same having a lateral lug 22 which is caused to be urged normally 50 against the upper end of a fixed stop device 23 on said post 20, the urging tendency of the lug in the direction just mentioned being brought about by the influence of a leaf spring 24 which is carried by the post 20 and which has its free end in yielding engagement with the inner face of the dog 21, as is best illustrated in Figure 5 of the drawings. As shown, the dog extends downwardly at an angle from a line drawn vertically from the edge of the transfer channel that is situated at one end of the assembling elevator so that the lower extremity of the dog is normally superposed with respect to the duplex rail when the latter is projected into the assembling elevator to support the matrices in the auxiliary or second elevation.

It is clearly illustrated that a spring 25 herein employed is attached at one of its ends to the transfer channel and its opposite end is fixed to the lever 18 to one side of the pivotal mounting of the latter, whereby the locking dog tends to normally seek the position last above referred to.

I have now set forth generally the various 90 mechanical details of construction of my improved line safety device whose duty in typographical composing and casting machines is to prevent the operator from accidentally sending a line through that is raised in the auxiliary position in the assembling elevator. That is to say, if the filling piece of the first elevator is in a position not to support the first elevator when display casting is done, the assembling elevator cannot be 100 raised until the duplex rail is manually withdrawn from an auxiliary position, or until the filling piece has been actuated manually and thrown over into the position shown in full lines in Figure 4. In the manner herein set forth, I am able to instantly cause the assembling elevator to lock until one or the other of the two above stated operations has taken place, and at that time only is it possible to send a composed line through the machine.

In Figure 4 of the drawings the first elevator filling piece has been turned to cam the lever 14 so that the lug 17 thereof presses against the tail piece of the lever 18, thus turning the latter in a direction contrary to the normal tension exerted thereupon by the aforesaid spring 25. In this movement of the lever 18, the normal position of the dog 21 shifts from a position in superposed relation to the portion A of the duplex rail to the position B of said rail, where it is now no longer an obstruction in the vertical path of movement of the assembling elevator. In consequence thereof it manifestly follows that the elevator may now proceed upward. When it is intended that the matrices shall be maintained at a position at the lower level of the assembling elevator, and thus sent through the machine, it will be necessary that 110 120 125 130

the duplex rail be first manually withdrawn, at which time the dog 21 is cleared from the duplex rail and the assembling elevator may proceed upwardly. In this view the first elevator positioning screw is illustrated at S in dotted lines and the path of the screw relative to the filling piece is indicated by the dot and dash lines L.

The dog 21, because of the relative arrangement of parts and the novel combination of elements herein recited, is thus positioned at the lower end of the intermediate transfer channel, with the spring 24 normally urging the lower end of said dog to a position 5 slightly into the adjacent end of the assembling elevator and in superposed relation to said duplex rail. The dog therefore simply overlies the duplex rail normally and serves to block or obstruct the path of movement 10 of the assembling mechanism. Through this novel manner of co-ordinating the parts and combining same for relative coaction, I am able to entirely eliminate interference with the intended position of the line of matrices 15 such as would cause same to be sent through the machine in "double block" position. This is primarily because of the fact that during the raising of the assembling elevator by the operator, no part of my device is brought 20 into frictional contact with any portion of the duplex rail that could possibly result in derangement in the intended order of the 25 matrices.

When the assembling elevator has been 30 raised, it may descend in regular course and in so doing the dog 21 is made to automatically adapt itself to the then existing conditions and when the elevator is in a full normal or assembling position again, the dog 35 is urged outward of the lower end of the transfer channel, where it once more assumes a position to automatically block upward movement of the elevator, assuming the duplex rail thereof to be in a position to support 40 the matrices at a second level. Upon the 45 blocking of the assembling elevator attention of the operator is directed to the condition which then presents itself, and if it is intended that the matrices should occupy the position 50 at the lower level, it will be required that the duplex rail be withdrawn manually and positioned out of the path of the lower extremity of the dog 21.

My device provides means whereby lines 55 can be sent through the machine in either normal or auxiliary positions, as may depend upon (1) an actuation imparted to the filling piece, or (2) a previous manual withdrawal of the duplex rail, and by oscillating the dog 21 laterally with respect to the duplex rail, there being normally slight clearance between the upper face of the latter and the lower blocking or obstructing end of the dog, no visible friction or end thrust is set up against the duplex rail or between the latter and any 60

part of the device that could possibly result in disturbing the composed line during intended upward movement of the assembling elevator.

I am broadly concerned with the novel 70 combination of elements which constitute my device or mechanism, the same consisting principally of a dog or other blocking device that may be the mechanical equivalent thereof structurally and functionally, that will 75 normally occupy a position in the assembling elevator where it will obstruct upward movement of said elevator, but which at no time bears directly or indirectly with the duplex rail during movement of the elevator 80 in an upward direction as may be induced by operations imparted thereto by the operator. I am also particularly concerned with the novelty of the device wherein a portion in the system employed will impart motion to the 85 dog in a lateral direction by an actuation set up in a filling piece of the first elevator and whereby, without disturbing the filling piece of said first elevator, the dog will be made to clear itself from the duplex rail when the 90 latter is manually withdrawn. I lay stress, too, upon the novel combination of a few movable co-ordinated parts between the first elevator filling piece and the dog or effective locking portion of the scheme employed. 95

Formed upon the lever 14 at a point just inwardly of the vertical lug 17 is a depending stop lug 26 adapted to come to rest against the back edge of the vise and to be confined thereagainst by the normal action of the 100 spring 25 when the blade 6b is removed from beneath the first elevator, as would be incident to an actuation set up at the knob 6a. In consequence thereof, it will be appreciated that provision is herein made for limiting 105 the movement of the cam surface 16 relative to the effective path of movement of the said blade 6b, thus positively insuring operation of the lever 14 at each impulse from the said 110 blade.

I claim:

1. In a typographical composing and casting machine, the combination of an assembling elevator wherein the matrices are composed in line at different levels and including an adjustable rail to fix the level of composition, a vise cap, an intermediate transfer channel, a first elevator filling piece, and an automatic line safety device carried by the vise cap and said intermediate transfer channel and including a means at the lower end of the intermediate transfer channel normally extending into the assembling elevator in the path of the aforementioned adjustable rail when the latter is in position to support the matrices at a second level and means co-operable with the filling piece during movement thereof for actuating the device to clear the dog from the rail when the latter is in said 115 last mentioned position. 120

2. In a typographical composing and casting machine, the combination of an assembling elevator wherein the matrices are composed in line at different levels and including an adjustable rail to determine the level of composition, a vise cap, an intermediate transfer channel, a first elevator filling piece and an automatic line safety device co-operable with the filling piece and with the assembling elevator when the latter is in one position to lock the assembling elevator and to unlock same when in another position and including a dog associated with the intermediate transfer channel and normally projected into the assembling elevator directly over a surface of the aforementioned rail to block movement of the assembly rail. 70
3. In a typographical composing and casting machine, the combination of an assembling elevator wherein the matrices are composed in line at different levels and including an adjustable rail to determine the level of composition, a vise cap, an intermediate transfer channel, a first elevator filling piece and an automatic line safety device co-operable with the filling piece and with the assembling elevator, when the latter is in one position to lock the assembling elevator and to unlock same when in another position and including a dog associated with the intermediate transfer channel and normally projected into the assembling elevator directly over a surface of the aforementioned rail to block movement of the assembling rail. 75
4. In a typographical composing and casting machine, the combination of an assembling elevator wherein the matrices are composed in line at different levels and including an adjustable rail to fix the level of composition, a vise cap, an intermediate transfer channel, a first elevator filling piece, an automatic line safety device operative in one position of the filling piece and the adjustable rail to engage the latter directly and lock the elevator, said device being movable in a horizontal direction over a course described by an arc of a circle between the front of the rail and the back thereof. 80
5. In a typographical composing and casting machine, the combination of an assembling elevator wherein the matrices are composed in line at different levels and including an adjustable rail to fix the level of composition, a vise cap, an intermediate transfer channel, a first elevator filling piece, an automatic line safety device operative in one position of the filling piece and the adjustable rail to engage the latter and lock the rail and including an oscillatory lever carrying a rail locking dog mounted thereon for pivotal movement on a horizontal axis. 85
6. In a typographical composing and casting machine, the combination of an assembling elevator wherein the matrices are composed in line at different levels and including an adjustable rail to fix the level of composition, a vise cap, an intermediate transfer channel, a first elevator filling piece, an automatic line safety device operative in one position of the filling piece and the adjustable rail to engage the latter and lock the rail and including an oscillatory lever carrying a rail locking dog mounted thereon for pivotal movement on a horizontal axis. 90
7. In a typographical composing and casting machine, the combination of an assembling elevator wherein the matrices are composed in line at different levels and including an adjustable rail to fix the level of composition, a vise cap, an intermediate transfer channel, a first elevator filling piece, an automatic line safety device operative in one position of the filling piece and the adjustable rail to engage the latter and lock the rail and including an oscillatory lever carrying a rail locking dog mounted thereon for pivotal movement on a horizontal axis. 95
8. In a typographical composing and casting machine, the combination of an assembling elevator wherein the matrices are composed in line at different levels and including an adjustable rail to fix the level of composition, a vise cap, an intermediate transfer channel, a first elevator filling piece, an automatic line safety device operative in one position of the filling piece and the adjustable rail to engage the latter and lock the rail and including an oscillatory lever carrying a rail locking dog mounted thereon for pivotal movement on a horizontal axis, and means for normally holding the lever in one position. 100
9. In a typographical composing and casting machine, the combination of an assembling elevator wherein the matrices are composed in line at different levels and including an adjustable rail to fix the level of composition, a vise cap, an intermediate transfer channel, a first elevator filling piece, an automatic line safety device operative in one position of the filling piece and the adjustable rail to engage the latter and lock the rail and including an oscillatory lever carrying a rail locking dog mounted thereon for pivotal movement on a horizontal axis, and means for normally holding the lever in one position. 105
10. In a typographical composing and casting machine, the combination of an assembling elevator wherein the matrices are composed in line at different levels and including a set of levers mounted to turn on vertical axes respectively at the vise cap and the intermediate transfer channel, means on one of the levers for engagement with the filling piece during movement of the latter in one direction and adapted to impart movement to both levers, means for disposing the first means normally in the said one path of movement of the filling piece, and means carried by the other lever for normal superposed presentation to the rail when the latter is in a position to support matrices at the second level in the assembling elevator and to thereby block movement of the elevator through its engagement with the rail and adapted when the first lever is actuated during said one movement of the filling piece to occupy an unobstructing position relatively to the rail and permit the elevator to be moved upward. 110
11. In a typographical composing and casting machine, the combination of an assembling elevator wherein the matrices are composed in line at different levels and including an adjustable rail to fix the level of composition, a vise cap, an intermediate transfer channel, a first elevator filling piece, an automatic line safety device operative in one position of the filling piece and the adjustable rail to engage the latter directly and lock the elevator, said device being movable in a horizontal direction over a course described by an arc of a circle between the front of the rail and the back thereof. 115
12. In a typographical composing and casting machine, the combination of an assembling elevator wherein the matrices are composed in line at different levels and including an adjustable rail to fix the level of composition, a vise cap, an intermediate transfer channel, a first elevator filling piece, an automatic line safety device operative in one position of the filling piece and the adjustable rail to engage the latter and lock the rail and including an oscillatory lever carrying a rail locking dog mounted thereon for pivotal movement on a horizontal axis, and means for normally holding the lever in one position. 120
13. In a typographical composing and casting machine, the combination of an assembling elevator wherein the matrices are composed in line at different levels and including an adjustable rail to fix the level of composition, a vise cap, an intermediate transfer channel, a first elevator filling piece, an automatic line safety device operative in one position of the filling piece and the adjustable rail to engage the latter and lock the rail and including an oscillatory lever carrying a rail locking dog mounted thereon for pivotal movement on a horizontal axis, and means for normally holding the lever in one position. 125
14. In a typographical composing and casting machine, the combination of an assembling elevator wherein the matrices are composed in line at different levels and including an adjustable rail to fix the level of composition, a vise cap, an intermediate transfer channel, a first elevator filling piece, an automatic line safety device operative in one position of the filling piece and the adjustable rail to engage the latter and lock the rail and including an oscillatory lever carrying a rail locking dog mounted thereon for pivotal movement on a horizontal axis, and means for normally holding the lever in one position. 130

locking dog mounted thereon for pivotal movement on a horizontal axis, means for normally holding the lever in one position, and means for yieldingly advancing the dog 5 to a normal position directly over the duplex rail.

10. In a typographical composing and casting machine, the combination of an assembling elevator wherein the matrices are composed in line at different levels and including an adjustable rail to fix the level of composition, a vise cap, an intermediate transfer channel, a first elevator filling piece, and a line safety device including a dog co-operable with 15 the rail to arrest movement of the elevator, a lever carrying the dog, a lever pivoted to

the vise cap and having a portion co-operable with the first lever and a portion disposed in the path of movement of the filling piece to be engaged thereby so as to set up motion in both of said levers and to change the position of the dog of the first lever relatively to the rail, means connected with the first lever to urge same in one direction, and stop means carried by the second lever and adapted to repose against a surface of the vise cap under 75 the action of the urging means so as to limit swinging movement of said second lever in one direction relatively to the said filling piece.
